UNITED STATES PATENT OFFICE

2,501,396

OIL BURNER WITH PREHEATING AND
IGNITING MEANSHenry J. Le Clerc, Cambridge, and Philip J.
Le Clerc, West Medford, Mass.

Application November 19, 1947, Serial No. 787,010

1 Claim. (Cl. 158—90)

1

This invention relates to new and useful improvements in oil burners and the primary object of the present invention is to provide a wickless automatic lighting oil burner.

Another important object of the present invention is to provide an oil burner including a heating unit and an igniter, and embodying novel and improved means for simultaneously energizing the heating unit and the igniter.

A further object of the present invention is to provide an oil burner including novel and improved burner sleeves so designed as to direct a flow of heat through the same with the maximum efficiency.

A still further aim of the present invention is to provide an oil burner that is simple and practical in construction, strong and reliable in use, neat and attractive in appearance, small and compact in structure, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a diagrammatic view showing the present oil burner applied to a source of fuel, and with parts of the burner shown in dotted lines;

Figure 2 is a similar view of Figure 1 and with parts of the burner broken away and shown in section;

Figure 3 is a transverse horizontal sectional view taken substantially on the plane of section line 3—3 of Figure 2;

Figure 4 is an enlarged fragmentary vertical sectional view taken substantially on the plane of section line 4—4 of Figure 5;

Figure 5 is an elevational view of the burner sleeves and fuel pan spaced relative thereto, and with parts of the sleeves and fuel pan broken away and shown in section; and,

Figure 6 is a transverse horizontal sectional view taken substantially on the plane of section line 6—6 of Figure 5.

Referring now to the drawings in detail, wherein for the purpose of illustration, there is disclosed a preferred embodiment of the present invention, the numeral 10 represents an annular heating unit having an upstanding flanged portion 12. Annular channels 14 and 16 are provided in this heating unit 10 and receive heat-
ing elements or coils 18 and 20 that are con-

nected to each other at one end. The free ends of these coils 18 and 20 are connected to depending terminals or posts 22 and 24 that extend beneath the unit 10.

5 An arcuate hollow rib 26, integrally formed at the bottom wall of the heating unit 10, is disposed between the channels 14 and 16. The ends of the rib 26 are in spaced opposed relation to form a passage between the channels 14 and 16. The rib 26 is provided with a plurality of circumferentially spaced openings 25 that register with circumferentially spaced openings 27 provided in an arcuate hollow upstanding rib 28 forming part of the bottom wall of an annular oil pan 30.

The oil pan 30 is supported on the heating unit 10 and the annular flange portion 12 embraces the oil pan 30 as shown best in Figure 2 of the drawings.

20 The oil pan 30 is provided with a central flanged portion 32 having an annular inner shoulder 34 that receives the lower edge of an inner perforated sleeve 36, an inner annular oil receiving channel 38 that receives the lower edge of an intermediate perforated sleeve 40, an outer annular oil receiving channel 42 that receives the lower edge of a further perforated intermediate sleeve 44, and an annular outer shoulder 46 adjacent its outer annular flange 48 that supports the lower edge of an outer perforated sleeve 50.

25 Fixedly positioned in the bottom wall 52 of the oil pan 30 and in the interrupted portion 53 between the spaced ends of the channel 28, is a carbon trapping leg 54 having an inlet nipple 56 that is connected to a conduit 58 leading from a conventional electric time clock and oil valve mechanism 60. The blind bore or chamber 62 provided in the carbon trapping leg 54 communicates with the oil receiving channels 38 and 42, 30 so that oil entering the chamber 62 from the conduit 58 will enter the oil pan.

35 Removably carried by the outer sleeve 50 is an electric igniter 64 that is connected to one terminal 66 of the mechanism 60 by an insulated wire 68. The other insulated wire 70 carried by this igniter 64 is connected to the terminal 22 of coil 18. Leading from the terminal 24 of coil 20, is a further insulated wire 72 that is connected to the remaining terminal 74 of the mechanism 60.

40 It should be noted that the intermediate sleeves 40 and 44 are notched as at 76 to accommodate the igniter 64, as best shown in Figures 2 and 5 of the drawings.

45 In practical use of the device, the time clock and valve mechanism 60 is connected to a fuel

line 78 leading from the sump or supply pan 80 of an elevated oil tank 82, and the plug 84 carried by the electric cord 86 of the mechanism 60 is inserted into a usual electric outlet. The electric time clock in mechanism 60 will be actuated to simultaneously energize the coils 18 and 20 and the igniter 64. The valve in the mechanism 60 will remain open at all times to permit a flow of fuel into the oil receiving channels 38 and 42. The heating coils 18 and 20 and igniter 64 will remain energized for a predetermined period of time to preheat the oil in the channels 38 and 42 so that vapor formed from the oil in the oil pan will be ignited. Once the oil in the pan has been ignited, the time clock in mechanism 60 will shut off the current, as the heat prevalent in the sleeves and the oil pan will be sufficiently heated to efficiently ignite the oil without having to retain the heating coils energized after the initial operation.

Having described the invention what is claimed as new is:

An oil burner comprising an annular heating unit having inner and outer annular walls, an arcuate rib provided between the inner and outer walls of said unit and dividing the same into inner and outer channels, said rib having a plurality of circumferentially spaced openings, the ends of said arcuate rib being in spaced opposed relation to form a passage between said channels, a resistance heating coil having a portion positioned in said inner channel and having one end anchored in said inner channel, said heating coil extending through said passage and having a portion positioned in said outer channel,

the other end of said heating coil being anchored in said outer channel, an annular oil pan having a concentric arcuate and hollow upstanding rib, the hollow rib of said oil pan having a plurality of circumferentially spaced openings registering with the openings in said first named rib, a carbon trapping leg carried by the oil pan and received in the passage between the ends of said first named arcuate rib, an inlet conduit connected to said carbon leg, an igniter carried by said oil pan overlying said carbon leg, a plurality of perforated, concentric sleeves rising from said pan, said heating unit and said pan having opposed, central openings, said carbon trapping leg including a cylindrical member having a blind bore communicating with the passage between the ends of said arcuate rib, and an outlet nipple projecting laterally from said cylindrical member and communicating with said blind bore intermediate the ends thereof, said sleeves having longitudinal slots receiving said igniter.
